UNITED STATES PATENT OFFICE.

GEORGE PAUL THOMAS, OF GLENSHAW, PENNSYLVANIA.

METAL-PUNCHING MACHINERY.

1,179,476.

Specification of Letters Patent.

Patented Apr. 18, 1916.

Application filed June 29, 1914. Serial No. 847,976.

To all whom it may concern:

Be it known that I, GEORGE PAUL THOMAS, residing at Glenshaw, in the county of Allegheny and State of Pennsylvania, a citizen of the United States, have invented or discovered certain new and useful Improvements in Metal-Punching Machinery, of which improvements the following is a specification.

10 My invention consists in improvements in metal-punching machinery and more particularly in mechanism for attaching the punch to the punching head.

In multiple punching machines a number 15 of punches are arranged in series side by side transversely of the punching head, to the end that corresponding holes may be punched side by side transversely of the work as it is fed through the machine beneath the punching head. The punches themselves have heretofore been secured to the ends of the spindles carried by the punching head by means of clamping nuts, and these nuts must be turned (for the purpose of applying and removing the punches) 20 by means of wrenches. It is necessary in a multiple punch in which the punches are so secured to the punching head, that the spaces between the adjacent spindles of the transverse row shall be sufficiently great to 25 permit of the action of the wrenches in applying and removing the punches; consequently, the punches cannot be arranged as close together in transverse row as they might otherwise be. This heretofore irreducible minimum distance between adjacent punches has been a limitation which the machine builder would gladly have been freed from; for often a closer spacing, if 30 practicable, would have been adopted.

By my invention, clearance does not have to be left for the insertion and action of wrenches; and, furthermore, the punches may be applied to and removed from the ends of the punching-head with the greatest ease and by the simplest operation, with a great saving of time otherwise consumed.

My invention is illustrated in the accompanying drawings in which—

50 Figure 1 is a vertical section through the chuck in which my invention consists applied to spindle of the punching head of a metal-punching machine and with the punch itself in place; Fig. 2 is a horizontal sectional view, on the line II—II, Fig. 1;

Fig. 3 is a sectional view, on the line III—III, Fig. 1; Fig. 4 is a view in elevation of the cam lever detached; Fig. 5 is a view similar to Fig. 1, showing a modification in detail; Fig. 6 is a like view, showing another modification; Fig. 7 is still another view similar to Fig. 1, showing the adaptation of the invention to punches of standard shape; and Fig. 8 shows a number of punches with shanks of varied shape, 60 but each adapted to be used in the practice of my invention.

Referring particularly to Fig. 1, the member with which the punching head is equipped and to which the punch is attached is shown in exemplary way, in the form of a spindle 1. Such a spindle is the usual member for attachment of the punch, but it will be understood that the invention is not limited to any particular form 70 of attaching member.

2 is the punch. As shown in Fig. 1, the punch 2 is applied in axial line against the end of spindle 1 and there secured. As said at the beginning, the punch has heretofore been secured to the spindle by means of a clamping nut, and it has been necessary to leave clearance between adjacent spindles to give access to a wrench for applying and removing.

In the place of a clamping nut, I employ a casing 3, the particular shape of which (as will presently appear) is subject to variation. This casing, unlike the clamping nut referred to (which is applied and removed with the punch), is applied to the punching head and remains secure while punches are applied to and removed from it. This casing 3 is provided with a seat for the punch which will preferably take the form of an orifice 4, axially arranged with respect to the spindle, for the reception of the punch, so that the punch 2 introduced through orifice 4 will abut against the end of the spindle 1, as is particularly 90 shown in Fig. 1.

The punch itself is provided with an abutment, which may take the form of a groove 5, and the casing 3 carries a block 6 which, when the punch 2 is brought to position, engages the notch 5 in the punch and holds it secure for operation. The engaging portions of the punch and of the block may, as will presently appear, be variously shaped, and union may be variously accom-

plished, but I will first describe specifically the construction shown in Figs. 1, 2, 3, and 4.

The casing 3 is provided with a lateral 5 prolongation which takes the form of a cylindrical arm 7. The cylinder is closed at the end with a perforate head 8, of which more will presently be said. Through this cylinder 7 and through the perforate head 10 extends the locking bolt 9, with an enlarged head 10, which locking bolt is impelled in a direction toward the punch by means of the spring 11, conveniently arranged between the cylinder head 8 and the 15 head 10 of the locking bolt itself. The head 10 of the locking bolt engages the locking block 6, the engagement is (as shown in Figs. 1 and 2) a dove-tailed engagement on a surface oblique to the direction of movement of the punch 2 when being applied. This relative movement of the block 6 and the bolt head 10 permits of nicety of adjustment, advantageous in case variation exists in the dimensions of the punches successively used—for, of course, this locking 25 mechanism is intended to be used for holding interchangeable punches.

The outer end of the locking bolt 9 has, pivoted to it, the cam lever 12, rotated by 30 hand. A cam surface *a* upon this hand lever, coöperating with an abutment preferably in the form of a roller 13 mounted on extensions of the cylinder 7, may be used to lock the bolt and the block 6 firmly, once 35 the punch is in place. Fig. 1 shows this cam surface *a* in such locking contact with roller 13. Consideration of Fig. 1 will make plain the fact that by turning cam lever 12 to the left such locking engagement may be broken, 40 and the locking block 6 left free to recede to the left against the tension of spring 11. Such is the open position of the chuck, and with the parts so positioned a punch 2 may be introduced in the opening 4 in the casing 45 3 and locked in place. The block 6 will recede (spring 11 being compressed) until, as the punch is forced upward, groove 5 comes opposite a correspondingly shaped 50 tongue on block 6, whereupon block 6 will spring outward to lock the punch in place. A second cam surface *b* is provided on cam lever 12; and this surface *b*, engaging a corresponding abutting surface (conveniently 55 formed on the cylinder head 8) when lever 12 is turned still farther to the left, will draw the bolt aside and with it the block 6, against the tension of spring 11, to release the tool 2. Two things will be understood respecting this cam lever and its 60 action: First, when in release position, that is when neither cam is engaging its abutting surface, the block 6 is held in position yieldingly by the tension of the spring 11 65 (permitting application of the punch) and, second, that the permissible play of the bolt

9 in longitudinal direction is as great as the distance *c d* (Fig. 2), the maximum play of the block 6 across the path of punch 2 when being applied and removed.

As particularly shown in Fig. 2, the locking block 6 does not extend circumferentially around the body of punch 2 so far as to interfere with ready application and removal.

As particularly shown in Fig. 5, it is 75 not necessary that the locking block 6 and the head 10 of the locking bolt be separate; they may be made a single member 14. In this case there is no provision for variation in the dimensions of different 80 punches; but these tools are made of standard size and, under ordinary conditions, special compensation such as is shown in Fig. 1 is not necessary.

In Fig. 6 I have shown in place of a 85 spring-backed lever-thrown locking block, a locking block in the form of a set-screw 15. It will be easily understood that this set-screw may be so arranged that operation of it will not require great clearance between adjacent punches.

In Fig. 7 I show that the casing 3 may be adapted in shape to the shape of a standard punch. This figure also shows that the casing itself may be provided with a shoulder 16 to engage the punch and sustain the thrust of the drawing out of the punch from a hole punched in a plate of metal. This shoulder 16 will preferably, though not necessarily, be supplementary to a corresponding shoulder formed on the locking block 14. As has been explained with respect to the locking block, the shoulder 16 will not extend more than half way around the shank of the punch. In this case (supplementary shoulders on casing and locking block being provided) the locking-block 14 will have a displacement twice as great as is otherwise necessary, to permit application 100 and removal of the punch. As I have already said, the recess in the shank of the punch need not be a continuous groove and indeed need not be a groove at all. It is only necessary that the engagement of punching block be by abutting surfaces extending 105 transversely of the line of strain and either punch or block may be recessed to accomplish that end and the recess may extend either part way or all the way along the punch as desired. In Fig. 8 I have shown a variety of shapes for the punch in this regard, and it will be understood that the locking block will be correspondingly shaped.

In another copending application, filed June 29, 1914, Serial No. 847,977, I am describing and claiming an oil feed, for the purpose of keeping the punch itself automatically oiled. It is sufficient here to note 110 that an oil chamber in the casing 3 is indi-

cated at 17, that oil grooves in the punch are indicated at 18, and that wick 19 for the feeding of the oil extends across the periphery of the opening 4 in the casing 3 and 5 when the punch is applied bears upon its surface.

I claim as my invention:

1. In a metal-punching machine, the combination of a punching head provided with 10 a transversely disposed seat for a punch, a casing borne by said head and provided with a punch-receiving opening, a punch in said opening abutting at its inner end against the seat of said punching head, and a punching 15 lock borne by said casing and movable laterally to and from punch-engaging position, said punch and said lock being provided with complementary strain-sustaining surfaces disposed transversely to the 20 longitudinal axis of the punch.
2. In a metal-punching machine, the combination of a punching head provided with a seat for a punch, a spring-impelled punch lock borne by said punching head, and 5 means for withdrawing said lock against the tension of its impelling spring.
3. In a metal-punching machine, the com-

bination of a punching head, a casing borne by said punching head, a locking bolt extending through an orifice in said casing, a 30 cam lever pivoted to the outer end of said locking bolt, and a bearing surface for said cam.

4. In a metal-punching machine, the combination of a punching head provided with 35 a seat for a punch, a spring-impelled bolt borne by said punching head, a double faced cam lever pivoted to the end of said bolt and two bearing surfaces arranged one opposite each of the cam faces of said cam 40 lever.

5. In a metal-punching machine, the combination of a punching head, a casing borne by said punching head and provided with an orifice for a punch, a spring actuated 45 bolt mounted in said casing and a punch-locking block borne by and movable upon said bolt.

In testimony whereof I have hereunto set my hand.

GEORGE PAUL THOMAS.
